CABLE CONNECTOR

Jay W. Atman, Canonsburg, Pa., assignor to Aluminum Company of America, Pittsburgh, Pa., a corporation of Pennsylvania

Application December 3, 1957, Serial No. 48,760

Term of patent 14 years

(Cl. D54—13)

Fig. 1 is a front elevational view of a cable connector embodying the new design, in a collapsed position;

Fig. 2 is a perspective view of the same;

Fig. 3 is a side elevational view of the connector;

Fig. 4 is a front elevational view of the connector in an operative position; and

Fig. 5 is a perspective view of the same.

I claim:

The ornamental design for a cable connector, substantially as shown.
